POGO STICK

Henry Rieth, Trumbull, Ohio, assignor to Kinsman Manufacturing Co., Kinsman, Ohio, a corporation of Ohio

Filed Apr. 1, 1968, Ser. No. 11,231

Term of patent 14 years

Int. Cl. D21—04

U.S. Cl. D34—5

FIG. 3

The side not shown is the mere image of the side shown and the back is similar in appearance to the front.

I claim:

The ornamental design for a pogo stick, as shown and described.
